DRILLING MACHINE

Filed March 3, 1922

UNITED STATES PATENT OFFICE.

ANDREW J. CARTER, OF DENVER, COLORADO.

DRILLING MACHINE.

Application filed March 3, 1922. Serial No. 540,911.

To all whom it may concern:

Be it known that I, ANDREW J. CARTER, a citizen of the United States, residing at Denver, in the county of Denver and State 5 of Colorado, have invented certain new and useful Improvements in Drilling Machines, of which the following is a specification.

This invention relates to drilling machines of the type in which a reciprocating hammer is caused to forcibly engage with the end of a rotating and longitudinally moving drill steel by the expansion of a helical spring against which it is intermittently retracted through the instrumentality 10 of a rotary crank-wheel.

A machine of the above described character has been shown and described in United States Letters Patent Nos. 1,069,853 and 1,115,898 granted to me on the twelfth 20 day of August, 1913, and on the third day of November, 1914, respectively, and it is the principal object of the present invention to provide in the constructions disclosed in the above mentioned patents, certain new 25 improvements which increase the usefulness and efficiency of the machine, and augment its practical value.

Another object of the invention resides in providing for the mechanical operation of 30 the impact mechanism of the drilling machine by an electrically driven motor which is mounted on the machine so as to form a component part thereof; a further object is to provide a readily controlled adjustment 35 for varying the stroke of the reciprocating hammer to any desired degree within the limits set by the proportions and relative arrangement of the operative parts of the retraction mechanism; and still another object resides in providing an easily adjusted 40 device of simple construction for pulling the drill steel from the hole in which it works, when the machine is withdrawn.

An embodiment of my invention has been 45 illustrated in the accompanying drawings in the several views of which like parts are similarly designated and in which—

Figure 1 is a side elevation of my improved drilling machine in its operative 50 position on a guide shell which, as in other

machines of this type, houses the screw by which the machine is advanced toward the face of the rock in ratio to the increasing depth of the hole produced by the intermittent impacts of the drill steel;

Figure 2 represents a longitudinal section 55 of the drilling machine taken on the plane indicated by the line 2—2 in Figure 3 and showing the electric motor which as stated before, is mounted on the casing of the machine, in elevation;

Figure 3, a longitudinal section taken on the line 3—3, Figure 2;

Figure 4, a fragmentary section along the line 4—4, Figure 3;

Figure 5, a section on the line 5—5, Figure 1, looking in the direction of the arrow drawn across said line;

Figure 6, a transverse section taken on the line 6—6, Figure 2, and Figure 7, an 70 enlarged view of the hook-shaped head of the pull bar of the machine.

Referring more specifically to the drawings, the reference numeral 2 designates the casing of the machine which, as usual, is composed of bolt-connected sections 3, 4 75 and 5 which when taken apart, afford access to the assembled parts of the operating mechanism.

A shaft 6 mounted for rotation in bearings on the sides of the casing at the rear end thereof, carries inside a chamber 7 a crank wheel composed of two parallel disks 8 and 9 which are separated by a spacing collar 7a and which are connected adjacent 85 their peripheral edges by a plurality of equidistantly arranged wrist pins 10.

Each wrist pin is provided with a loosely surrounding roller 12 to reduce friction during its contact with the pull bar of the 90 reciprocating hammer as will hereinafter be described, and it will be understood that although in the drawings but three wrists have been shown, their number may be increased or decreased according to the frequency 95 of the hammer strokes desired during each revolution of the shaft.

The disk 9 of the crank wheel is enlarged in thickness and provided with gear teeth for its co-operative engagement with a 100

pinion 13 on a short transverse shaft 14 in the upper portion of the chamber 7, which through the medium of a pair of meshing miter gears 15 and 16, is operatively connected with the shaft of an electric motor contained in a housing 17 which is mounted upon the casing of the drill.

Inasmuch as the construction of the motor is not a part of the present invention, its mechanism has not been shown in the drawings, it being sufficient for the purpose of explaining the operation of the improved impact apparatus, to state that its rotor is connected with a suitable reduction gearing inside the housing, of which the protruding shaft on which the gear wheel 16 is mounted, is the driven member.

The cylindrical hammer-chamber 18 of the casing, forward of the crank-chamber 7, is partially lined with a bushing 19 of steel or other wear-resisting material, which can be readily removed and replaced.

Fitted for reciprocation in the lined portion of the chamber, is a reciprocating hammer 20 which is flattened at opposite sides to reduce friction and prevent its binding in the cylindrical guiding surface.

The hammer is connected at the end of a rearwardly extending pull bar or pitman 21 by means of a pivot joint which is formed of a transverse cylindrical boss 22 at the end of the rod, rotatably fitted in a correspondingly formed recess in the rearward portion of the hammer.

25 The recess is open at one end as shown in Figure 6 of the drawings, and after the pitman is in place therein, its end is closed by a plug 23. The pull bar 21 has at its free, rearward end an offset hook-shaped head 24 which in the rotary movement of the shaft 6, is intermittently engaged by the wrists on the crank-wheel.

A spring-supported prop provides a yielding support for the bar in its operative position, and an adjusting appliance engaging the upper surface of the bar times the periods of its operative engagement with the crank-wheel during the rotary movement of the shaft.

50 The yielding support consists of an arm 25 pivotally attached to the apertured head of a bolt 26 which is secured in an opening in the rear wall of the casing by a nut 27.

The arm is supported in an inclined position upon a spiral spring 28 which is seated in a depression in the bottom of the casing and it carries at its free end, an anti-friction roller 29 which engages with the underside of the pitman.

55 The stroke-adjusting appliance consists of a transverse shaft 30 rotatably supported in bearings at opposite sides of the crank chamber near its juncture with the hammer chamber, and provided with a forwardly extending arm 31 which engages the upper

surface of the pull bar, and with a crank-arm 32 at right angles thereto, which has a pivotal connection with the end of an adjusting screw 33.

The threaded outer portion of the screw 70 works in a correspondingly threaded nut 34 which is loosely fitted in an opening in the rear wall of the casing and is held against longitudinal displacement by an integral head 35 at its outer end, and a nut 36 applied to its opposite end.

A hand crank 37 on the head of the nut 34 provides for its manual rotation when it is desired to regulate the operative position of the pull bar relative to the crank 80 wheel, by longitudinal adjustment of the screw.

Interposed between the hammer and a shoulder at the rear end of the hammer-chamber, is a helical spring 38 which when compressed by the rearward movement of the hammer through the operative action of the crank wheel upon the pull bar, provides the power by which the hammer when subsequently released, is impelled to forcibly engage with the end of a drill steel 39 longitudinally movably mounted at the forward end of the casing.

The drill steel is held in a chuck 40 which is rotatably supported in a sleeve 41 extending forwardly of the front head 5 of the casing, and the chuck carries for its rotation in the operation of the machine, a gear wheel 42 which meshes with a pinion 43 at the end of a shaft 44 extending through a bore of 100 the casing formed parallel to the hammer chamber.

The shaft which is supported in bearings at the ends of the bore, is provided with a worm wheel 45 which meshes with a worm 105 46 on the crank shaft.

In order to feed water to the point of contact of the drill steel with the rock and thereby prevent loss in temper by overheating, the steel has an axial bore through 110 which water supplied at its rearward end inside the casing, may flow to the cutting edges at its opposite end.

The water is supplied to the bore of the drill steel through a U-shaped tube 47 which 115 extends into the hammer chamber through a slot in the bushing 19 with one of its ends projecting loosely inside the orifice of the bore.

The opposite portion of the tube positioned in a recess 48 of the casing outside of the hammer chamber, extends through a gland 49 and a rubber packing 50 in an opening of the front head of the casing, for its connection with a flexible conduit attached 120 to a conveniently located source of water supply.

The steel puller hereinbefore referred to consists of a yoke 52 which straddles the drill steel forward of the sleeve on the front 130

head of the casing and which is hinged as at 53, between lugs at the rear end of the head through the medium of an angularly disposed arm 54.

5 The arm has a projection 55 which by frictional contact with a surface of the head, holds the yoke against accidental displacement, and a lip 56 at the point of juncture of the arm with the yoke proper is provided 10 to facilitate moving the appliance about its pivotal axis for the removal of the drill steel.

The inner face of the yoke opposite to the end of the sleeve on the front head of the 15 casing, has a recess to receive a collar 57 on the drill steel, provided to limit the longitudinal movement of the same.

The drilling machine constructed as hereinabove described, is as usual, mounted for 20 longitudinal movement on a guide-shell 58 which in practice, is adjustably fastened to a column or other suitable support.

The guide shell contains the usual feed screw by which the machine is advanced to 25 the work, and the casing of the machine is supported upon a so-called mounting slide 59 which by means of a sleeve 60 is operatively connected with the feed screw.

30 The casing is connected with the slide 59 through the medium of a chain 61 attached at its ends to lugs at the sides of the slide and placed in a circumferential depression at the rear end of the casing, and links 62 which are pivotally connected with the slide 35 and engage over hook-shaped lugs 63 at opposite sides of the casing nearer the front end of the same.

Inasmuch as the method of mounting the 40 machine and the means for feeding it to the face of the rock, do not differ materially from those at present used on other machines of similar character, no details thereof have been shown in the drawings, other than those hereinbefore described.

45 In the operation of the machine, the guide shell is as usual, mounted on a column or other suitable support, and the machine is advanced by rotation of the feed screw until the cutting end of the drill steel engages 50 with the face of the rock.

The electric motor which is connected with a conveniently located source of electricity by means of conductors 64 extending through an opening of its housing, is now 55 energized by reversal of a switch controlling the current flow through its circuit and the movement of its rotor is through the medium of the reduction gearing and the miter-gears 15 and 16, transmitted to the pinion 13 60 which by engagement with the gear wheel 9 causes the crank shaft to rotate in its bearings at a greatly reduced rate of speed.

During the rotary movement of the shaft in the direction of the arrow shown in Figure 2, the equidistantly arranged wrists of

its crank wheel will successively engage with the hook-shaped head of the pull bar and thereby cause the hammer to be retracted against the resistance of the spring which thereby is compressed. 70

After the pull bar has been drawn rearwardly to an extent predetermined by its normal elevation, its head is disengaged from the wrist with which it was in contact, by the downward movement of the next 75 succeeding wrist engaging with its stem, and the hammer being thus released, is by the sudden expansion of the spring forcibly impelled to strike against the end of the drill steel and thereby cause the same to cut 80 into the rock.

The hammer has in its forward portion, a groove 65 as shown in Figure 3 of the drawings, to admit the curved water tube 47 when it approaches the end of its forward 85 stroke.

It will be understood that while the machine is in operation, the drill is continuously rotated at a comparatively slow velocity by the rotary movement of the shaft 44 90 which through the medium of the worm gearing, is compelled to move synchronously with the crank shaft.

The length of stroke of the hammer may 95 be regulated by adjustment of the arm 31 engaging with the pitman, it being evident that as the latter is lowered, the period between the engagement of its head with each crank pin and its subsequent disengagement from the same is proportionately shortened. 100

The spring pressed arm 25 holds the pull bar continuously in engagement with the wrist of the crank wheel and the loose fit of the nut 34 of the adjustment in the opening of the rear wall of the casing, permits of 105 the adjusting screw following the arcuate movement of the arm 32 when the shaft 30 is moved about its axis of rotation.

The steel puller is effective only when the 110 drill steel is withdrawn from the hole produced in the operation of the machine, when by engagement with the collar on the steel it compels the latter to move rearwardly with the machine and thereby prevents its sticking in the rock.

Having thus described the several improvements in the construction of my drilling machine, in the most practical and simplest form at present known to me, I desire it understood that variations in the details 120 of construction and the arrangement of their parts may be restored to within the spirit of the present invention as defined in the hereunto appended claims. 115

What I claim and desire to secure by Letters Patent is:

1. In a rock drill of the character described, the combination of a spring-urged reciprocating hammer, a pull bar in pivotal connection therewith, a rotary crank inter- 125

mittently acting upon the pull bar, a spring-urged element loosely engaging a side of the pull bar to yieldingly maintain its operative relation with the crank, and an adjustable stop loosely engaging an exterior face of the pull bar in opposition to said element to limit the movement of the pull bar by action of the element.

2. In a rock drill of the character described, the combination of a spring-urged reciprocating hammer, a pull bar in pivotal connection therewith, a rotary crank intermittently acting upon the pull bar, a movable spring urged element loosely engaging a side of the pull bar to yieldingly maintain its operative relation with the crank, a stop capable of pivotal adjustment and loosely engaging the pull bar in opposition to said element, and means to effect the adjustment of the stop.

3. In a rock drill, a casing, a drill steel projecting through an end thereof and provided with a collar, mechanism in the casing

for the operation of the drill steel, and a steel puller comprising an arm pivoted on the casing, a yoke on the arm at one side of the pivotal axis, straddling the steel for engagement with its collar, and a projection on the arm at the opposite side of the axis, frictionally engaging the casing. 30

4. In a rock drill, a casing, a drill steel projecting through an end thereof and provided with a collar, mechanism in the casing for the operation of the drill steel, and a steel puller comprising an arm pivoted at one end on the casing, a yoke extending angularly at the outer end of the arm and straddling the steel for engagement with its collar, a projection at the pivoted end of the arm, frictionally engaging the casing, and a 40 lip at the outer end of the arm to move it about its pivot against the frictional resistance of the projection.

In testimony whereof I have affixed my signature.

ANDREW J. CARTER.
